UNITED STATES PATENT OFFICE.

GEORGE H. BLACK, OF ROCHESTER, NEW YORK, ASSIGNOR TO UNITED SHOE MACHINERY CORPORATION, OF PATERSON, NEW JERSEY, A CORPORATION OF NEW JERSEY.

METHOD OF MAKING INSOLES.

Original application filed December 28, 1918, Serial No. 268,639. Divided and this application filed March 5, 1921. Serial No. 449,669.

To all whom it may concern:

Be it known that I, GEORGE H. BLACK, a citizen of the United States, residing at Rochester, in the county of Monroe and 5 State of New York, have invented certain new and useful Improvements in Methods of Making Insoles; and I do hereby declare the following to be a full, clear, and exact description of the invention, such as will 10 enable others skilled in the art to which it appertains to make and use the same.

This invention relates to a method of preparing shoe insoles of the type having a sewing rib and an outer margin or feather, 15 and more particularly to welt insoles in which, because of the fitting to which they are subjected or other causes, the surface of the body stock at the inner side of the rib is higher than the surface of the margin at 20 the outer side of the rib.

The method may be employed with especially important advantages in the production of women's high grade shoes which, in accordance with the present trade demands, must have extremely pointed toes and an appearance of lightness at the toe of the shoe. In preparing insoles for such shoes it is difficult for the operative to channel around the toe without distorting it and 25 without weakening the between substance at the base of the sewing rib by making the turn at the toe prematurely, as those skilled in the art will understand. It is 30 important, therefore, that before the inseaming operation is performed the toes of such insoles be moulded to the shape and form required for the style of shoe in which they are to be incorporated. In the inseaming operation also, the operative is apt to 35 swing the shoe prematurely when sewing at the toe of a pointed toe shoe, resulting in a further weakening of the sewing rib by reason of the resultant oblique perforation of the between substance by the sewing needle. It is desirable, therefore, that the toe, 40 in addition to being shaped, should have the base of the sewing rib consolidated to give as much additional strength thereto as possible as an offset to the probable weakening 45 resulting from the channeling and inseaming operations. To this same end it is cus-

tomary, when the stock is not first grade, to apply a canvas strengthening element to the sewing rib. Several types of insole employ such a reinforcement notably the Gem, Cole Patent No. 575,460, and the Economy, Johnson Patent No. 849,245, although variations of the reinforcement shown in these 55 patents have been employed in other insoles. In all, however, the plane of the insole inside the sewing rib lies above that at the outside, making it difficult to locate the inseam sufficiently low to provide the desired 60 "closed" welt crease. It is important, therefore, that the stock in the angle at the 65 inner side of the sewing rib be depressed so that the inseaming operative will not be forced to sew "high" and thus spoil the appearance of the shoe by leaving a "grinning" 70 seam.

The objects of the present invention are to overcome all of the difficulties just adverted to and thus, by superior shoe making, produce the desired appearance and style 75 effect in the finished shoe.

The present method will best be understood from a description thereof in connection with a machine or apparatus particularly designed for use in practising the method. Such a machine is disclosed in the 80 inventor's co-pending application Serial No. 268,639, filed December 22, 1918, from which application the present application is a division.

The drawings of said parent application 85 are repeated here, Fig. 1 showing a perspective view of the machine; Fig. 2 an enlarged view of the sewing rib shaping and insole compressing instrumentalities; Fig. 3 the toe of a pointed toe insole before treatment; 90 and Fig. 4 the same insole after treatment.

The machine or apparatus comprises a base plate 2 provided with ribs 4 supporting gibs 5 to provide a seat for a work support 6 which is recessed in its upper face to a 95 depth equal to the thickness of the feather of the insoles to be treated, the recess being shaped to receive the toe end of the insole. The gibs also provide a slideway for a forked rib-shaping member 10 movable in close, 100 sliding contact over the insole feather and against the outer side of the sewing rib.

- The shaping member 10 is connected by a link 12 with an operating hand lever 13 by which said member may be forcibly advanced over the feather of the insole to iron it down at the outer base of the sewing rib (particularly if the feather is cut on a bevel) and to shape the sewing rib to the predetermined outline or pattern of the acting edge of said member.
- 10 The machine further comprises a triangular form or inner shaping member 15 removably secured to a plunger 16. Form 15 accurately fits the inner side of the sewing rib in the intended position and shape of 15 the rib and supports the rib throughout its entire height against the molding or shaping thrust of the member 10, as shown in Fig. 2. On its lower face the form 15 is relieved in the center, or recessed, so that the 20 downwardly extending margin thus formed will enter the channel, produced by the upturning of the inner lip or channel flap which is cut around the margin of the insole, with the result that the downward 25 pressure of the form is concentrated along a line or narrow surface at the inner base of the sewing rib, where the canvas reinforcement overlies the channel. The form and plunger are operated by a lever 18 and 30 connection 20 to a foot treadle to apply a uniform heavy, concentrated, downward pressure for depressing and compacting the insole stock simultaneously along a line at the inner base of the rib at both sides of the 35 toe and for forming at the inner base a depressed seat for the inseam stitches, as just described. The compression of the stock and lateral shaping pressure applied through the member 10 condense the rib stock in a 40 manner to increase its strength or resistance to tearing under the puncturing action of the needle in sewing the inseam. Where, as usual and as shown in the drawings, the sewing rib comprises a plurality of plies of stock, as one or two lips of leather and one or more thicknesses of reinforcing fabric, the action of this apparatus in compacting and molding the rib stock into a multi-ply structure imparts additional strength to the rib as well as shapes it with exactness and uniformity to the precise outline desired for the inseam. The arrangement by which the shaping members 10 and 15 act upon the 45 stock at the root of the rib at both its inner and outer bases affords particular efficiency in shaping and molding the rib so that the inseam can be sewn low, making it possible to obtain a closed welt crease and a thin, graceful toe on women's pointed-toe shoes.
- 50 In order that the finished shoe may closely follow the lines of the last, as intended by the shoe designer, and present a stylish and graceful appearance, it is extremely important that the sewing rib of the insole 55 should be made very accurately and uni-

formly since it is the position of the sewing rib which eventually gives the shoe the desired appearance.

With the present practice of making insoles it is necessary to temper, as with water, the insole stock to enable it to be channeled to form the sewing rib. The channeling operation, however, tends to distort the stock when in tempered condition and in the drying out of the sole the sewing rib is further 75 distorted by shrinkage. The rib sets in this condition. When the shoe upper and welt are attached to the sewing rib in this condition the upper and welt, of course, do not follow the intended lines. Moreover, when 80 the shoe upper is lasted to a distorted sewing rib the lasting wipers which are intended to conform accurately to the lines of the last at the toe can not wipe the upper against the sewing rib as they should with the result 85 that in the subsequent welting operation the shoe upper and welt can not be properly in-seamed. By molding and shaping the sewing rib, particularly at the toe where the worst distortion is found to occur, a uniform and accurate setting of the sewing rib is obtained and consequently the subsequent 90 welting operation is facilitated and the shoe upper and welt are enabled to follow the lines intended for them in the finished shoe. 95

A gas burner 25 is shown by which the shaping form 15 can be heated and thus facilitate the insole shaping operation. The plunger 16 is normally pressed up in its guideway in the frame by a spring 26. The 100 support 28 for the body portion of the insole is attached to the base plate 2 separately to permit substitution of a different toe support 6, and the supports 6 and 28 are spaced apart to present a finger recess for the operator's convenience in applying and removing 105 insoles.

In practising the present method with the aid of the illustrated machine, the operator stands at the left of the machine and thrusts the insole endwise with his left hand to force the feather at the toe into the recess of the upper face of the support. After the insole has been properly introduced he depresses the shaping form 15 into the toe of 115 the insole, depressing the insole stock along the inner base of the rib and positioning said form to co-operate with the forked member 10 which is then advanced by the lever 13 in the right hand of the operator 120 to complete the shaping of the rib, all as fully described above.

Those skilled in the art will recognize that the toe lip-shaping operation herein described may be performed on various types of welt insoles with attainment of the beneficial results referred to, and the invention is not confined, therefore to operating upon the Economy type of welt insole shown 125 in the illustrations.

The nature and scope of the invention having been indicated and the preferred mode of practising the method having been described, what is claimed as new, is:—

- 5 1. That improvement in the art of making insoles having a channel formed by turning a lip outwardly and upwardly to produce a sewing rib which comprises applying a concentrated pressure to the insole stock in said 10 channel simultaneously throughout the length of a line extending around the toe at the inner base of the rib sufficiently to depress the surface at said base relative to the surface at the outer base of the rib.
- 15 2. That improvement in the art of making insoles which comprises applying to the insole concentrated vertical pressure simultaneously throughout the length of a line around the toe at the inner base of the sewing 20 rib of the insole and thus depressing and compacting the insole stock at the inner base relative to that at the outer base of the rib.
- 25 3. That improvement in the art of making insoles having a channel inside the sewing rib and a reinforcement in said channel which comprises molding the sewing rib at the toe to the desired shape and applying sufficient pressure to the channel within the 30 shaped toe to compress the body stock and lower the plane of reinforcement overlying said channel.
- 35 4. That improvement in the art of making insoles which consists in applying pressure with heat to the sewing rib at the toe of an insole throughout substantially the entire height of the rib and simultaneously along both sides of the toe to compress the stock laterally and mold the rib.
- 40 5. That improvement in the art of making insoles which consists in compacting the insole stock around the toe by pressure to
- depress its surface at the inner base of the sewing rib and molding the rib by transverse pressure applied simultaneously at 45 both sides of the toe.
6. That improvement in the art of making insoles which consists in depressing the insole stock by pressure at the inner base of the sewing rib and molding the rib transversely, said depressing and molding operations being effected simultaneously at the two sides of the toe.
7. That improvement in the art of making insoles which consists in applying simultaneously along both sides of the toe of an insole concentrated pressure vertically downward upon the insole stock at the inner base of the sewing rib and while such pressure is maintained molding the rib transversely. 60
8. That improvement in the art of making insoles which consists in embracing the pointed toe of an insole along the outer side of the sewing rib, supporting the rib at its inner side, depressing the insole stock by 65 concentrated pressure applied along a line at the inside base of the lip and compressing the rib transversely while the depressing pressure continues.
9. That improvement in the art of making insoles having a channel formed by turning a lip outwardly and upwardly to form a sewing rib which comprises positioning an insole with the bottom face of its toe portion against a work support, applying 70 concentrated pressure to the insole thus supported throughout the length of a line extending around the toe at the inner base of the sewing rib sufficient to depress the surface of said base relative to the surface at 75 the outer base of the rib, and thereafter molding the rib by transverse pressure. 80

GEORGE H. BLACK.
